UNITED STATES PATENT OFFICE

HERBERT S. HUMPHREY, OF KALAMAZOO, MICHIGAN, ASSIGNOR TO RUUD MANUFACTURING COMPANY, OF PITTSBURGH, PENNSYLVANIA

WATER HEATER

Application filed May 7, 1928. Serial No. 275,723.

The main object of this invention is to provide an improved water heater which is comparatively compact, of large capacity and efficient in the matter of utilization of 5 heat units of the fuel consumed.

Objects pertaining to details and economies of my invention will definitely appear from the description to follow. The invention is defined in the claims.

10 A structure embodying the features of my invention is clearly illustrated in the accompanying drawings, in which:

Fig. 1 is a vertical central section of my improved water heater taken on line 1—1 15 of Figs. 2 and 3.

Fig. 2 is a horizontal section on line 2—2 of Fig. 1.

Fig. 3 is a horizontal section on line 3—3 of Fig. 1.

20 Fig. 4 is a side elevation of the base or burner chamber unit of my improved heater.

Fig. 5 is a side elevation of the casing body unit of my improved heater.

25 Fig. 6 is a side elevation of the casing top unit of my improved heater.

Fig. 7 is a side elevation of the intermediate reservoir or boiler unit of my improved heater.

30 Fig. 8 is a side elevation of the inner reservoir or boiler unit of my improved heater.

Fig. 9 is a side view of a portion of the inlet water supply pipe.

35 Referring to the drawings, my improved heater in the embodiment illustrated comprises a base unit 1 constituting a burner chamber, the burner 2 being arranged therein. Above and supported by this burner is

40 a casing unit designated generally by the numeral 3 and comprising concentric outer and inner walls 4 and 5 providing an annular reservoir 6. These walls are quite close together so that a relatively thin body

45 of water is contained therein. The casing unit has an upwardly converging bottom member 7, the upper end of which is disposed through a flanged opening in the horizontal wall 8 and seamed over the same

50 at 9. These walls 7 and 8 coact to provide

an annular passage 10 at the bottom of the casing unit with which the discharge valve 11 is connected.

The gas supply valve 12 is controlled from a thermostatic mechanism indicated 55 at 13 subject to the water drawn from the heater. The thermostat and gas valve are conventionally illustrated.

A drain pipe 14 opens through the bottom member 8 of the casing unit so that 60 any condensation collected on the bottom member 8 is discharged into the burner chamber or otherwise, as may be desired.

The top casing unit designated generally by the numeral 15 is formed of an outer wall 65 16 and an inner wall 17 joined at their edges to provide a water reservoir 18. The lower end of this casing top unit is adapted to fit within the upper end of the casing body unit, the units being formed separately and assembled by fitting the lower end of the casing top unit within the body unit.

70 The casing top unit is provided with a flue opening 19.

The water heating reservoirs 6 and 18 75 have a circulating connection, preferably external, in the form of a pair of elbows 20 and 21 connected by the union 22. This external connection is readily accessible and

also it does not interfere with the arrangement of the additional reservoirs within the casing.

Within the casing I mount an inner cylindrical annular reservoir 23 and an intermediate cylindrical annular reservoir 24, 85 these reservoirs being double-walled and the walls being arranged quite close together. These reservoirs are arranged concentrically relative to each other and to the casing.

90 The reservoirs 23 and 24 are connected at their lower ends by the couplings 25 providing a circulation connection from the inner reservoir to the intermediate reservoir.

The inner reservoir is provided with a 95 head 26 at its upper end having vent openings 27 therein for the passage of the products of combustion. These vent openings, however, are not of such capacity as to carry off all the heated gases and products of 100.

combustion so that a substantial portion thereof is compelled to travel outwardly around the outside of the inner reservoir and into contacting relation with the casing and intermediate reservoir.

5 The water supply pipe 28 is connected to a coupling 31 at its lower end mounted in the casing unit 4 and projects upwardly within the inner reservoir member, being connected to a central coupling 32 in the head.

10 The upper end of the intermediate reservoir is connected to the top casing unit reservoir, the connection preferably consisting of a cross pipe 29 connected at its ends to the upper end of the intermediate reservoir and the T pipe or conduit 30 connected centrally to the cross conduit 29 and its arms connected to the top unit reservoir.

15 20 This provides for quite an effective distribution of the water through the reservoirs as it circulates therein.

25 My improved water heater is highly efficient, a large heat absorbing area being exposed to the products of combustion. In practice the casing or exterior of the heater may be provided with insulating material, but this is not illustrated as it forms no part of my invention.

30 35 My improved heater is of large capacity in proportion to its size and is highly efficient in the matter of utilization of the heat units of the fuel.

Having thus described my invention what I claim as new and desire to secure by Letters Patent is:

1. In a water heater, the combination of a cylindrical double-walled casing unit constituting a water reservoir, said casing reservoir having a discharge at the bottom thereof, a double-walled casing top unit constituting a water reservoir and having a central vent opening therethrough, said casing water reservoirs having a circulating connection, inner and intermediate cylindrical annular water reservoirs disposed concentrically relative to each other and to said casing unit, the lower ends of said inner and intermediate water reservoirs having opposed circulating connections, said inner reservoir having a head at its upper end provided with vent openings, a water supply conduit disposed within said inner water reservoir and connected centrally to said inner reservoir and the lower end of said supply conduit being connected to a coupling disposed in said casing, and a circulating connection for the upper end of said intermediate water reservoir to said casing top reservoir consisting of a cross conduit opening at its ends to said intermediate reservoir and a T-shaped conduit connected to the center of said cross conduit and to said top unit water reservoir.

65 2. In a water heater, the combination of a

cylindrical double-walled casing unit constituting a water reservoir, said casing reservoir having a discharge at the bottom thereof, a double-walled casing top unit constituting a water reservoir and having a central vent opening therethrough, said casing water reservoirs having a circulating connection, inner and intermediate cylindrical annular water reservoirs disposed concentrically relative to each other and to said casing unit, the lower ends of said inner and intermediate water reservoirs having opposed circulating connections, said inner reservoir having a head at its upper end provided with vent openings, a water supply conduit disposed within said inner water reservoir and connected centrally to said inner reservoir and the lower end of said supply conduit being connected to a coupling disposed in said casing, and a circulating connection for the upper end of said intermediate water reservoir to said casing top reservoir.

3. In a water heater, the combination of a burner chamber, a burner within said chamber, a cylindrical double-walled casing unit constituting a water reservoir and having an upwardly converging bottom portion provided with a central opening above said burner, said casing having a discharge vent at the top, said casing water reservoir having a discharge at the bottom thereof, a double-walled casing top unit constituting a water reservoir and having a central vent opening therethrough, said casing water reservoirs having a circulating connection, inner and intermediate cylindrical annular water reservoirs disposed concentrically relative to each other and to said casing unit, the spaces between said casing, inner and intermediate reservoirs being open at the top and bottom for the free circulation of the products of combustion therethrough to said vent at the top of said casing unit, the lower ends of said inner and intermediate water reservoirs having opposed circulating connections, a water supply conduit connected to the upper end of said inner water reservoir, and a circulating connection for the upper end of said intermediate water reservoir to said casing top reservoir.

In witness whereof I have hereunto set my hand.

HERBERT S. HUMPHREY.
